UNITED STATES PATENT OFFICE.

SAMUEL T. WHITE, OF DAVENPORT, IOWA.

DESIGN FOR A HANGING VASE.

50,329.

Specification for Design.

Patented Feb. 13, 1917.

Application filed August 19, 1916. Serial No. 115,906. Term of patent 7 years.

To all whom it may concern:

Be it known that I, SAMUEL T. WHITE, a citizen of the United States of America, and resident of Davenport, in the county of Scott and State of Iowa, have invented a new, original, and ornamental Design for Hanging Vases, of which the following is a specification, reference being had to the accompanying drawing, forming part hereof.

The figure in the drawing is a perspective view of a hanging vase for plants and the like, embodying my design.

I claim:

The ornamental design for a hanging vase, as shown.

SAMUEL T. WHITE.

Witnesses:

G. E. LAU,
EVA L. BLEAU.
